ELECTROMAGNETIC VIBRATING DEVICE

Application filed June 21, 1930. Serial No. 462,907.

This invention relates to magneto electric vibrating devices, and more particularly to telephone receivers.

The invention has been made especially 5 with the idea of providing a telephone receiver for use as the earphone of a hearing aid device. Earphones, or earpieces, forming part of such devices for use by deaf people are desirably made as small and inconspicuous as possible, and a special object 10 of the present invention is to secure in a receiver to be used for this purpose high electrical efficiency combined with the utmost economy in space occupied. The invention 15 is, however, not limited in its use to earphones, but is applicable to telephone receivers generally and to other vibrating devices in which the vibratory armature of the device does work other than the production 20 of sound.

Telephone receivers as commonly heretofore made comprise a permanent magnet, usually of horseshoe or U-form, with coils placed around the legs or polepieces of the magnet, these coils being connected to a source of audio frequency current. The field of the permanent magnet in combination with the variable alternating field produced by the coils furnishes the force which 25 actuates the diaphragm. The useful part of this force is proportional to the product of the two flux densities, that is, the density of the permanent flux and that of the variable 30 flux. As the path of the alternating flux is through the permanent magnet itself, and as the A. C. reluctance of the permanent magnet and the saturated pole pieces is relatively 35 high, the efficiency is necessarily low. And 40 furthermore, because of the magnet having to carry the variable flux produced by the coil, it has not been practicable to make the magnet of steel of the highest coercive force and correspondingly low permeability, and 45 the practice has been to compromise by using steels which do not give the highest magneto motive force but which have a better permeability, thus sacrificing some of the possible magneto motive force to be furnished by the magnet in order to get a suit-

able result from the flux produced by the variable current in the coil.

I have largely increased the effective vibromotive force of devices of the kind referred to and reduced the size of the device 55 by providing in combination with a permanent magnet a separate path of low reluctance for the alternating flux, the construction being such that the alternating flux has a separate path of high permeability and is 60 mixed with the permanent flux only at and near the narrow, interpolar air gap, that is, at the place where it has to produce the useful force. By such construction, not only is 65 a more efficient use made of the energizing current traversing the coil, but it is possible to use magnets made of material, such as cobalt steel, having an extremely high coercive force and which furnish a very high 70 magneto motive force.

A telephone receiver according to the invention in the form I now consider best comprises two U-shaped permanent magnets which are placed in line with the legs of the same polarity adjacent each other, and a 75 double U, or E-shaped, core member of soft iron or other suitable metal of high permeability which is placed to extend in a direction transverse to the permanent magnets and with its intermediate leg between the adjacent legs of the permanent magnets, the two inner legs of the permanent magnets and the intermediate leg of this member combined forming a central leg or core the upper 80 end of which serves as a common pole piece. An energizing coil is placed around this central leg and pole piece, and the other pole piece of the magnets is provided by a plate, preferably of soft iron or other metal of high 85 permeability, which has a central opening into which the first pole piece extends with a narrow interpolar air gap therebetween, and which extends outward to the outer legs of the permanent magnets and of said double 90 U-shaped core member. Said core member 95 provides paths of low reluctance for variable flux produced by the coil which are separate from the permanent flux paths of the permanent magnets except where these paths are brought together at the common pole pieces 100

and air gap. The construction provides substantially separate metallic paths of different magnetic characteristics for the variable and the permanent fluxes and permits the use of 5 the most desirable materials for each, and thereby greatly increases the efficiency of the device, and at the same time conserves space, so that the vibromotive force is high relatively to the space occupied.

10 The accompanying drawings illustrate a telephone receiver embodying the invention in the form I now consider best. The particular device shown is intended for use as the earphone of a hearing aid apparatus.

15 Such earphones are commonly made in two general forms, one having a flat cover piece or cap substantially as shown in the drawings for application to the outside of the user's ear, and the other being a smaller instrument intended to be inserted into, or a part thereof inserted into, the aural cavity of the ear. In this smaller type, the instrument is necessarily more compact and has smaller parts. I have selected an instrument 20 of the larger kind for clearness of illustration, and the drawings are considerably enlarged from the actual size of the instrument. In said drawings:

Fig. 1 is a broken plan view of a telephone receiver embodying the invention;

Fig. 2 is a transverse sectional view taken on the line 2—2 of Fig. 1;

Fig. 3 is a similar view taken on the line 3—3 of Fig. 1, at right angles to Fig. 2;

Fig. 4 is a sectional view in plan taken on the line 4—4 of Fig. 2;

Fig. 5 is a plan view of a plate constituting a common pole piece;

Figs. 6 and 7 are side views of the member 40 providing the variable magnetic circuit and of one of the permanent magnets, respectively;

Fig. 8 is a cross sectional view of the diaphragm member; and

Fig. 9 is a side view of a modified divided form of the member shown in Fig. 6.

Referring to the drawings, the operative parts of the receiver are mounted within a casing comprising a cup-shaped housing 10 and a cap piece 11 which screws on to the exteriorly threaded end of the housing and is of a diameter to fit against the ear of the wearer and is provided with a central opening 12 for the escape of sound waves from the diaphragm of the instrument.

Seated within the housing 10 are two U-shaped permanent magnets 15 arranged in line diametrically across the housing chamber with their legs of like polarity adjacent 60 each other. A double U-, or E-shaped, core member 16 of soft iron or other metal of high permeability extends diametrically across the housing chamber between and at right angles to the magnets 15. The magnets 15 are thus arranged symmetrically one on

each side of the core member 16, with the intermediate leg 17 of the member 16 between the inner legs of the magnet 15 so as to form collectively a central core the upper end of which serves as a common pole piece 18 for the magnets 15 and core member 16. The magnets 15 and the two ends of the core member 16 thus radiate from the central pole piece 18. The position of the intermediate leg of the core member with relation to the two permanent magnets is such as to avoid saturation of the leg by the permanent flux. This is important, since if so saturated the leg would have a relatively high reluctance.

An energizing winding or coil 20 extends about the central core and pole piece between it and the outer legs of the magnet and core member. The coil is mounted on a spool 21 of insulating material, and the ends of the coil are connected to contact terminals 22 which when the spool is placed in position engage the inner ends of bushings or sockets 23 set in the wall of the housing 10 and adapted to receive connecting terminals of conductors for supplying the energizing current to the coil.

Another common pole piece is formed by a plate or disc 30, preferably of soft iron or other metal of suitably high permeability, 95 having a central opening 31 somewhat larger than the end of the pole piece 18 and openings or notches 32, 32 and 33, 33 to receive the ends of the outer legs of the magnet 15 and of the core member 16. This pole plate 100 is set over the coil with the ends of the outer legs of the magnet and core member in the notches 32 and 33 and with the end of the pole piece 18 extending into the central opening 31 to form therebetween a common air gap 34 for the several magnetic circuits. This interpolar air-gap, as shown at 34 is narrow, being not much greater than twice the width of the air-gap between the armature and the pole pieces. The diaphragm 110 member 40 mounted over the plate 30 may be of any suitable construction. As shown, it comprises a thin metal diaphragm carried by a peripheral ring 41 and provided with a central thicker portion 42 to serve as the armature. The armature extends over the pole piece 18 and air gap 34 and partly over the plate 30 so as to bridge over the air gap and be in the combined flux field.

In order to accommodate the diaphragm ring 41, the plate 30 is near its periphery flanged downwardly and then outwardly, its outwardly extending flange 43 seating on a shoulder 44 in the side of the housing, and providing a seat for the diaphragm ring 41, spacing rings 45 being used to secure the desired positioning of the pole plate and the diaphragm with relation to each other and to the pole 18. To reduce eddy currents, the plate 30 has a slot 46a extending inward

from one of the notches 33 to the central opening 31. Slots 46 extend from the other notch 33 and the two notches 32 part way toward the opening 31. This thin pole piece 5 30 surrounding the end of the pole piece 18 contributes materially to the economy of space in the receiver.

When an energizing current is supplied to the coil, the alternating flux produced by the 10 coil finds two paths of low reluctance through the central pole piece 18, each radiating portion of the core member 16, a portion of the pole plate 30, air gap 34 and the armature, and most of the alternating flux 15 takes these paths. Only a very small portion of the alternating flux passes through the permanent magnets because of their high A. C. reluctance. At the same time the flux 20 of the permanent magnets is flowing in paths consisting each of the central pole piece, one of the magnets 15, a portion of the pole piece 30, air gap 34 and the armature. A part of the permanent flux will be lost over the shunt path from the center legs of the permanent 25 magnet to the center portions of the soft iron cores 16, then through the soft iron cores to the pole piece 30 and there through to the outer legs of the permanent magnets. The junctions between the outer ends of the soft 30 iron cores and the pole pieces form points of relatively high reluctance, due to the notches at 33, so that this shunt flux is held down within limits at which the permanent as well as the induced fluxes passing through 35 the air-gap have the most favorable values. There are thus provided two complete magnetic circuits for the permanent magnetic flux and two complete magnetic circuits for the variable flux, and the variable flux circuits are separate from the permanent flux circuits except where they join at the common pole pieces and the air gap and the armature. The two fluxes thus have for the 40 most part separate paths, being combined, however, at the place where they contribute to the production of the useful force. It is thus possible to use permanent magnets of material having very high coercive force, such as cobalt steel, which because of their 45 extremely low permeability are not suitable for use when they have to carry alternating flux.

The area of the central pole piece may by 50 beveling off the ends of the inner legs of the permanent magnets be made as small as desirable for securing the greatest force on the armature, the area being desirably smaller as the thickness of the armature is less. In this way thorough superimposition and intermingling of the permanent and induced 55 fluxes at the point of action on the armature is obtained. This intermingling of the fluxes may be further increased by making the end 60 of the intermediate leg of the soft iron core member protrude somewhat beyond the ends

of the legs of the permanent magnets to furnish the entire effective pole area, as shown, for example, in Fig. 9.

It is to be understood that the invention is not limited to the particular construction and arrangement of parts shown in the drawings and to which the foregoing description has been largely confined, but that it includes departures therefrom within the claims. The use of the terms "A. C." and "alternating" as applied to the flux and to the current fed to the coil is not to be taken as implying that devices according to the invention are useful only when the coil is supplied with a purely alternating current. The invention is also useful when supplied with what is commonly termed a pulsating current. Such a current may be considered as comprising a D. C. component and an A. C. component.

The two permanent magnets 15 form in effect a double **U** magnet, and the **E**-shaped core member 16 forms with the coil a double **U** variable magnet. Obviously, it is not necessary that the permanent magnet be made in two separate parts and the variable magnet continuous from end to end, and the invention is not in its broader aspect limited to this construction. I consider it more desirable, however, to have it so, rather than to make the double **U** permanent magnet continuous and the variable magnet, or core member in two separate parts, as shown, for example, in Fig. 9.

Nor is the invention considered broadly limited to a single coil device having a double **U** permanent magnet and a double **U** variable magnet core member combined to form a single central common core and pole piece about which the single coil is placed. A two coil receiver according to the invention might for example have two **E**-shaped core members combined with three **U**-shaped permanent magnets, or with one **U**-shaped permanent magnet, to form two common poles, one for each coil.

What is claimed is:

1. A vibrator, comprising a plurality of permanent magnets of **U** shape, and a variable magnet having an **E**-shaped core member of metal of high magnetic permeability, legs of said permanent magnets of like polarity being disposed on opposite sides of the intermediate leg of said core member to constitute a common pole piece.

2. A vibrator, comprising a plurality of permanent magnets of **U** shape, an **E**-shaped core member of metal of high magnetic permeability, legs of like polarity of said permanent magnets being disposed on opposite sides of the intermediate leg of said core member to constitute a common pole piece, a coil surrounding said common pole piece, and a plate forming another common pole piece having an opening and positioned to

provide a common air gap between the edge of said opening and the first said pole piece and extending outward to the outer legs of said magnet and core member.

- 5 3. A vibrator, comprising a double **U** permanent magnetic structure of metal of high coercive force, a double **U** magnetic core of metal of high magnetic permeability, said magnetic structure and core extending transversely of each other and their inner legs forming a common pole piece, a coil between said pole piece and the outer legs of the magnetic structure and core, means providing a second pole piece forming an air gap about 10 the end of the first said pole piece and extending outward to said outer legs, and a vibratory armature mounted adjacent to said pole pieces and extending over the air gap.

- 15 4. A vibrator, comprising a double **U** permanent magnetic structure of metal of high coercive force, a coil mounted between the inner and the outer legs of said magnetic structure, means providing a path of low A. C. reluctance for flux produced by said 20 coil, and an armature vibrated by changes in the flux produced by said coil.

- 25 5. A vibrator, comprising flux paths for separate permanent and variable magnetic circuits, the permanent magnetic circuits being formed of high reluctance material and the variable magnetic circuits being formed of low reluctance material, both the permanent and variable magnetic circuits extending radially in a common plane from a common 30 pole piece formed by portions thereof and an armature adjacent to said plane for vibration in a direction perpendicular thereto.

- 35 6. A vibrator, comprising means providing a plurality of flux paths terminating in a central common pole piece, a plate having a central opening and overlying said means and forming an air gap about said pole piece, and a vibratory armature mounted outside of but adjacent to said air gap.

- 40 7. A vibrator, comprising both permanent and alternating current magnets having legs terminating in substantially a single plane, certain legs of said magnets constituting a common pole piece, and a metallic member lying in substantially the plane of the ends of said legs and being connected to legs of said magnets to form a second common pole piece and forming an air gap with 45 the first-named common pole piece.

- 45 8. A telephone receiver, comprising a permanent magnet having legs, a separate variable magnet having legs, juxtaposed legs of said magnets constituting a common pole piece, a metallic member engaging other legs of said magnets and forming an air gap about said common pole, and a diaphragm member providing an actuating armature positioned in the combined flux fields of said magnets at said air gap.

9. A telephone receiver, comprising two **U**-shaped permanent magnets set in line with their legs of like polarity adjacent each other, an **E**-shaped core member of metal of high magnetic permeability set at right angles to the permanent magnets with its intermediate leg between the inner legs of the permanent magnets, the inner legs of the permanent magnets and the intermediate leg of the core member combined forming a central core and pole piece, a coil surrounding said central core and pole piece, a plate of metal of high magnetic permeability set over said coil having a central opening to receive the end of the central pole piece and to define an air gap therewith and having openings to receive the ends of the outer legs of the permanent magnet and the core member, and a diaphragm member providing an actuating armature positioned in the combined flux field of said magnets and said core member at the air gap.

10. A vibrator comprising a vibratory armature, two separate magnetic circuits on one side of said armature, one circuit including a permanent magnet of relatively low magnetic permeability while the other circuit includes an electromagnet having a core of relatively high magnetic permeability, and both of said circuits consisting substantially wholly of magnetic material except for a relatively narrow air-gap substantially parallel to but adjacent said armature and having substantially parallel adjacent portions extending through the coil of the electro-magnet in a general perpendicular direction toward the central part of said armature, whereby the flux through the armature is a mixture of the fluxes produced by the permanent magnet and the electromagnet.

11. A vibrator comprising a vibratory armature, a winding disposed on one side of said armature, a core within said winding, having its upper end adjacent said armature and comprising a permanently magnetized part of relatively low magnetic permeability and a non permanently magnetized part of relatively high magnetic permeability, adapted to form an electromagnet when a current flows through said winding, whereby the flux through the armature is a mixture of the fluxes produced by the permanent magnet and the electromagnet, and magnetic material extending from the lower ends of said core upwardly around said winding and inwardly to within a short distance from the upper ends of said parts to provide magnetic circuits consisting substantially wholly of magnetic material except for a relatively narrow air-gap adjacent said armature.

12. A vibrator comprising a circular vibratory magnetically operated diaphragm, means for producing a flow of magnetic flux substantially along the axis of vibration of

said diaphragm, then radially outwardly with respect to said diaphragm across a relatively narrow air-gap substantially parallel to but adjacent said diaphragm, then away from the diaphragm adjacent the periphery thereof and finally radially inwards, said means including both a permanent magnet and an electromagnet whereby the flux operating the diaphragm is a mixture of the 10 fluxes produced by the permanent magnet and the electromagnet.

13. An electromagnetic vibrator, comprising an inducing coil adapted to be traversed by alternating current, a permanent magnet 15 core extending through said coil, a shunt core of non-retentive, highly permeable magnetic material providing a relatively low reluctance path for variable flux induced by said coil, common pole pieces for said cores 20 forming a gap for the fluxes passing through said cores so that the permanent flux of one core and the induced alternating fluxes of the other core enter the gap substantially superimposed and intermingled, with the permanent flux predominating the induced flux 25 in the gap, and a member actuated by the variations of the intermingled flux in said gap.

14. An electromagnetic vibrator, comprising an inducing coil, an inner core member extending through said coil and having at one end a central pole piece, a plurality of permanently magnetized core members extending from the opposite end of the inner 35 core member around said coil, a highly permeable non-retentive magnetic core shunting said permanent magnet core members to provide a relatively low reluctance path for variable flux induced by said coil, said core 40 members having a common pole piece forming with said central pole piece a gap, said pole pieces and said cores being so arranged that the permanent fluxes and the induced alternating fluxes of said cores enter the gap 45 substantially superimposed and intermingled, with the permanent flux predominating the induced flux in the gap and a member actuated by the variations of the intermingled flux in said gap.

15. An electromagnetic vibrator, comprising an inducing coil, an inner core member extending through said coil and having at one end a central pole piece, a plurality of permanently magnetized core members 55 radially extending from the opposite end of the inner core member around said coil, highly permeable non-retentive magnetic core members shunting said permanent magnet core members to provide a relatively low reluctance path for variable flux induced by said coil, said core members having a common pole piece forming with said central pole piece a gap, said pole pieces and said core members being so arranged that the permanent fluxes and the induced alternating 60

fluxes of said core members enter the gap substantially superimposed and intermingled, with the permanent flux predominating the induced flux in the gap and a member actuated by the variations of the intermingled flux in said gap. 70

16. An electromagnetic vibrator, comprising an inducing coil adapted to be traversed by alternating current, an inner core portion extending through said coil and having at one end a pole piece, said inner core portion comprising a permanently magnetized core member and a non-retentive highly permeable core member united at said pole piece 75 so that the permanent flux of one member is superimposed and intermingled at the pole piece with induced alternating flux in the other core member, a second pole piece forming a gap with said first pole piece and so joined to the other ends of said core members that the permanent and alternating fluxes of the core members enter into the gap superimposed and intermingled, with the permanent flux predominating the induced 80 flux and a member actuated by the variations of the intermingled flux in said gap. 85

17. An electromagnetic vibrator, comprising an inducing coil adapted to be traversed by alternating current, an inner core portion extending through said coil and having at one end a pole piece, said inner core comprising a permanently magnetized core member and a non-retentive highly permeable core member united at said pole piece so that the permanent flux of one member is superimposed and intermingled at the pole piece with induced alternating flux in the other core member, outer permanently magnetized and non-retentive core members extending 90 from the other ends of said inner permanently magnetized and non-retentive core members, respectively, around said coil, a second pole piece forming a gap with said first pole piece and so joined to the outer ends of said outer core members that the permanent and alternating fluxes of the core members enter into the gap superimposed and intermingled with the permanent flux predominating the induced flux, and a member actuated by the variations of the intermingled flux in said gap. 100

In testimony whereof I have hereunto set my hand.
